UNITED STATES PATENT OFFICE.

LOREN E. CLARK, OF MEADVILLE, PENNSYLVANIA.

IGNITION AND STARTING MECHANISM FOR INTERNAL-COMBUSTION ENGINES.

1,075,763.

Specification of Letters Patent. Patented Oct. 14, 1913.

Application filed February 7, 1913. Serial No. 746,865.

To all whom it may concern:

Be it known that I, LOREN E. CLARK, a citizen of the United States, residing at Meadville, in the county of Crawford and State of Pennsylvania, have invented new and useful Improvements in Ignition and Starting Mechanism for Internal-Combustion Engines, of which the following is a specification.

10 This invention relates to ignition and starting mechanism for internal combustion motors, the broad object of the invention being to do away entirely with the use of batteries and the trouble arising therefrom, 15 it being well understood by engineers that approximately ninety per cent. of the trouble experienced in internal combustion motors comes from some fault or difficulty in the batteries now in common use. Batteries have also been found to be unnecessarily expensive to maintain, whereas the mechanism of this invention is maintained at a minimum expense, and is always in working order for the purpose of generating 20 an electric current and transmitting the same to the spark plugs or other ignition points or devices.

With the above and other objects in view, the nature of which will appear in the following description, the invention consists 30 in the construction, combination and arrangement of parts, as will be hereinafter more fully described, illustrated in the accompanying drawings, and pointed out in 35 the claims hereunto appended.

In the drawings: Figure 1 is a side elevation, partly broken away, of the mechanism or apparatus of this invention. Fig. 2 is a side elevation of the motor used for primarily actuating the shaft of the generator. Fig. 3 is a side elevation of the rotor. Fig. 4 is a sectional view of the governor mechanism and the parts adjacent thereto. Fig. 5 is an edge view of one of the frame members 40 of the governor. Fig. 6 is a cross section taken on the line 6-6 of Fig. 4. Fig. 7 is a detail view of one end of one of the governor arms, showing the presser foot thereof.

Referring now to the drawings, 1 designates the generator which may consist either of a dynamo or magneto, the same embodying a shaft 2 which, in the case of a dynamo or magneto, will be the armature shaft.

The shaft 2 is extended considerably in 50 both directions beyond and outside of the

casing of the generator, as clearly shown in Fig. 1, and to one end of said shaft is secured a rotor, illustrated in detail in Fig. 3, and shown conventionally as comprising an annular series of buckets or vanes 3, a rim 4 60 to which the same are secured, a hub 5 which may be keyed or otherwise fastened to the shaft 2, and a web or spokes 6 connecting the hub 5 and rim 4.

The rotor referred to is mounted in a suitable casing 7, which is liquid or fluid tight and is provided with two inlet nozzles 8 and 9, through either of which compressed air, water or the like may be admitted for the purpose of driving the rotor in either direction, the casing being also provided with an outlet or exhaust nozzle 10.

The motor illustrated in detail in Figs. 2 and 3 is designed to be driven either by compressed air or water under pressure, thereby 75 causing the rotor to drive the shaft 2 at a speed which will enable the generator 1 to produce an electric current for conveying sparks to the ignition elements of an internal combustion motor (not shown). The 80 motor just hereinabove described is shown as bolted, at 11, to a flange or fixed collar 12 on the shaft 2, so that when not needed, the motor as a whole may be detached and removed therefrom. 13 designates grease or 85 oil cups for supplying lubricant to the shaft 2. At the opposite side of the generator 1, the shaft 2 has mounted thereon a friction wheel 14. This wheel is not keyed or splined to the shaft 2, but may be said to 90 be normally loose thereon. However, in its normal condition, the wheel 14 is frictionally held so as to rotate with the shaft 2 by the means to be described. The wheel 14 is prevented from moving off the end of the 95 shaft by means of a nut 15, or any equivalent stop, connected with the end of the shaft 2.

At a distance from the wheel 14 and adjacent to the hub of the generator 1, a ratchet wheel 16 is mounted on the shaft 2 in fixed relation to the latter, said wheel being shown as fastened to the shaft by means of a key 17. At the outer side of the ratchet wheel 16 is a pawl carrier 18 having a circumferential flange 19, on which is pivotally mounted a pawl 20 which engages the teeth of the ratchet wheel 16, and in this connection it may be noted that the pawl 20 may be reversed or thrown entirely over the pivot 21 110

- thereof, so as to operate in either direction in connection with the ratchet wheel 16.
- The wheel 14 is provided at its inner side with a friction face 22, while the pawl carrier 18 is provided on its adjacent side with a friction face 23. Between the friction faces 22 and 23, a governor is mounted. This governor comprises the oppositely arranged frame members 24 and 25, the said members 10 being of disk form and being loosely mounted on the shaft 2 in spaced relation to each other, as best illustrated in Fig. 4. The member 25 is provided on its outer side with a friction face plate 26 adapted to work in 15 contact with the friction face 22 on the wheel 14, and the member 24 is provided with a corresponding disk-shaped friction face plate 27 which is adapted to coöperate with the friction face 23 of the pawl carrier 18.
- 20 The members 24 and 25 are normally pressed apart by means of a coiled expansion spring 28 surrounding the shaft 2 and bearing terminally against said frame members 24 and 25.
- 25 Each of the frame members 24 and 25 is provided with a combined bracket and guide arm 29 extending substantially parallel to the shaft 2 and having its end slotted, as shown at 30, to receive one of a pair of governor arms 31, each of which is threaded, as shown at 32, to receive a weight or ball 33 which is internally threaded to engage the threaded portion 32 of the arm, thereby providing for moving the weight 33 nearer to 35 or farther from the pivotal point of the governor arm. Each governor arm is connected to the arm 29 of one of the frame members by means of a pivot 34 passing through the slot 30, above referred to, and each arm is 40 provided at the end opposite the weight 33 with a curved presser foot 35, the extremity of which is rounded, as shown at 36, and lies in sliding contact with the outer face of one of the frame members 24.
- 45 By reference to Figs. 1 and 2, it will be observed that one of the governor arms is pivotally connected to one of the frame members, while the other governor arm is similarly connected to the other frame member. 50 Therefore, under the centrifugal action of the governor arms, the frame members 24 and 25 are pressed toward each other, overcoming the tension of the expansion spring 28 and relieving the frictional engagement 55 between the frame members of the governor and the friction faces of the wheel 14 and pawl carrier 18. At any speed below a certain predetermined speed, however, the spring 28 is of sufficient strength to maintain the 60 frictional engagement between the governor frame members and wheel 14 and pawl carrier 18, under which condition the wheel 14 and the pawl carrier 18 are maintained in driving engagement with the shaft 2.
- 65 From the foregoing description, it will

now be understood that when the speed of the fly wheel of the internal combustion motor, in contact with which fly wheel the friction wheel 14 operates, reaches a point above the proper speed at which to drive the generator 1, the governor arms, by centrifugal action, will move outwardly, so as to compress the spring 28 and effect a disengagement between the friction wheel 14 and the shaft 2. This prevents driving the armature shaft of the dynamo and magneto at too high a speed.

When the internal combustion motor is at rest, air or water under pressure is admitted to the auxiliary motor casing 7, and this motor then serves to take up and drive the shaft 2 at a speed which will generate the necessary current in the dynamo or magneto 1, thereby furnishing the necessary spark to ignite the explosive mixture in the combustion chamber of the engine. As soon as the engine has been started by hand, for example, the sparking apparatus will take care of itself, and after the engine is running under its own power, the motor 7 may be thrown out of operation by cutting off the inflowing air or water under pressure.

The mechanism may also be used as a starter for one or more engines, by removing the friction wheel 14 and ratchet wheel 16, and throwing the motor 7 into operation, and turning the engine either by hand or by any other means, until the first explosion has been obtained. When the engine has attained sufficient speed, the electric current will be transferred by a suitable switch from the starter to the current furnished by the magneto driven by the engine being started.

While I have only referred to the friction wheel 14 as being placed in driving engagement with the fly wheel of the internal combustion motor, it will, of course, be apparent that the wheel 14 may be driven by a belt, sprocket, or other driving mechanism from the shaft or other rotating part of the engine, without departing from the spirit or sacrificing any of the advantages of the invention, hereinabove set forth. The separate intake nozzles 8 and 9, which are substantially tangential to the rotor in the casing 7, provide for actuating said rotor in either direction, while the pawl 20 by being made reversible is capable of operating in either direction on the shaft of the generator.

What is claimed is:

1. The combination with an internal combustion engine, of ignition mechanism for the same comprising a rotary electric generator, a friction wheel loose on the shaft 125 of the generator, a friction clutch automatically controlled by the speed of said shaft operating to throw said friction wheel and shaft into and out of driving engagement, and a motor independent of the engine for 130

driving the shaft of the generator preparatory to the driving action of the friction wheel.

2. The combination with an internal combustion engine, of ignition mechanism for the same comprising a rotary electric generator, a friction wheel loose on the shaft of the generator, a clutch including a speed governor automatically controlled by the speed of said shaft operating to throw said friction wheel and shaft into and out of driving engagement, a motor independent of the engine for driving the shaft of the generator preparatory to the driving action of the friction wheel, the governor embodying a pair of frame members in spaced relation to each other and slidable on said shaft, one of said members being movable into and out of engagement with a friction face on said wheel, an expansion spring for spreading said frame members apart, and governor arms acting to press said members toward each other.

3. The combination with an internal combustion engine, of ignition mechanism for the same comprising a rotary electric generator, a friction wheel loose on the shaft of the generator, a clutch including a speed governor automatically controlled by the speed of said shaft operating to throw said friction wheel and shaft into and out of driving engagement, and a motor independent of the engine for driving the shaft of the generator preparatory to the driving action of the friction wheel, the governor embodying a pair of frame members in spaced relation to each other and slidable on said shaft, one of said members being movable into and out of engagement with a friction

face on said wheel, an expansion spring for spreading said frame members apart, governor arms acting to press said members toward each other, a ratchet wheel on said shaft, a pawl carrier normally loose on said shaft and adapted to be engaged by one of said frame members, and a pawl on said carrier.

4. The combination with an internal combustion engine, of ignition mechanism for the same comprising a rotary electric generator, a friction wheel loose on the shaft of the generator, a clutch including a speed governor automatically controlled by the speed of said shaft operating to throw said friction wheel and shaft into and out of driving engagement, and a motor independent of the engine for driving the shaft of the generator preparatory to the driving action of the friction wheel, the governor embodying a pair of frame members in spaced relation to each other and slidable on said shaft, one of said members being movable into and out of engagement with a friction face on said wheel, an expansion spring for spreading said frame members apart, governor arms acting to press said members toward each other, a ratchet wheel on said shaft, a pawl carrier normally loose on said shaft and adapted to be engaged by one of said frame members, and a reversible pawl on said carrier.

In testimony whereof I affix my signature in presence of two witnesses.
